UNITED STATES PATENT OFFICE.

JAMES P. MAGENIS, OF NORTH ADAMS, MASSACHUSETTS.

CARBURETING-LAMP.

SPECIFICATION forming part of Letters Patent No. 400,096, dated March 26, 1889.

Application filed May 22, 1888. Serial No. 274,704. (No model.)

To all whom it may concern:

Be it known that I, JAMES PATRICK MAGENIS, of North Adams, in the county of Berkshire and State of Massachusetts, have 5 invented a new and Improved Carbureting-Lamp, of which the following is a specification, reference being had to the annexed drawings, forming a part thereof, in which—

Figure 1 is a central vertical transverse 10 section of my improved gas-burner. Fig. 2 is a horizontal section taken on line $x-x$ in Fig. 1. Fig. 3 is a horizontal section taken on line $y-y$ in Fig. 1, and Fig. 4 is a central vertical transverse section of the burner 15 with the chimney and the carbon-receptacle removed.

Similar letters of reference indicate corresponding parts in all the views.

My invention is an improvement in the 20 class of regenerative gas-lamps having a hydrocarbon-receptacle, through which the gas supplied to the burner is passed, for the purpose of enriching it, and thereby increasing the brilliancy of the light.

25 My invention consists in the construction and arrangement of the hydrocarbon-receptacle and gas-conducting tubes with reference to the annular or Argand burner ordinarily employed in lamps of this type. The 30 gas supplied to the lamp or burner enters a vertical centrally-arranged tube, A, within whose upper portion, g , is arranged a tube, b , for conducting the gas upward to the receptacle, whence it passes between the tubes

35 A and b downward to horizontal radiating-tubes c , that connect with the annular vertical burner B, having exits d . The tube b has much less diameter than its inclosing-tube, so that an annular space is left between them, as 40 shown. To the tube A is attached a circular plate, C, upon which are placed short vertical tubes e f , concentric with the tube A. The top of the tube e is about even with the top of the annular burner B, and the top of the 45 tube f extends a short distance above the said annular burner.

In the tube e is secured a conical ring, D, which inclines toward and projects a short distance above the top of the annular burner 50 B. The tube e , below the conical ring D, is perforated to admit air to the burner, and the tube f , below the burner, is also perforated to

admit air to the interior of the flame below the burner. The tube A extends above the partition a and above the top of the tube f , 55 and is threaded to receive the smaller end of the conical receptacle E.

In the receptacle E is axially arranged a tube, g , which corresponds in size with the tube A. The tubes A g inclose the tube b , 60 and both tubes communicate with the upper part of the receptacle E. The receptacle E is closed at the top by a screw-cap, E', which is removed whenever the receptacle is to be 65 filled.

To the exterior of the tube e are attached springs h , for receiving the glass chimney F.

The tube A is screwed on in the place of an ordinary burner, and the receptacle E is partly filled with the hydrocarbon, which may 70 be volatilized by the heat from the burner B. Gas enters the burner through the tube A, passes upward through the tube b , and is discharged into the receptacle E, where it becomes charged with the vapors of the hydrocarbon contained in the upper part of the receptacle. The gas returns and enters the tube g , and passes down between the tubes g and b to the partitions a , then outward through the tubes c to the annular burner B, where it burns at the orifices d , forming 75 an annular sheet of flame, which is deflected outwardly by the conical lower end of the receptacle E. The air entering the lower part of the tube e is divided, a portion of it 80 passing upward between the burner B and the conical ring D, another portion passing upward through the tube f , supplying air to the upper part of the flame. Still another portion passes upward between the tube f 85 and the inside of the burner B, supplying air to the base of the flame.

By admitting air to different portions of the flame in the manner described a very perfect combustion is secured, which permits of 90 introducing a large proportion of carbon into the gas, thereby increasing the whiteness and intensity of the flame, and at the same time economizing gas.

Having thus described my invention, I claim 95 as new and desire to secure by Letters Patent—

In a carbureting-lamp, the combination, with the annular burner, of the conical or downwardly-tapered hydrocarbon-receptacle

E, having a removable cap and arranged above and concentric with said burner in the described proximity thereto, whereby the flame may impinge on its lower portion, the 5 two gas-conducting tubes extending axially through the said receptacle nearly to the top and one arranged within the other, and the

horizontal tubes τ , which connect the burner with the lower portion of the outer tube, as shown and described.

JAMES P. MAGENIS.
